UNITED STATES PATENT OFFICE.

WILLIAM E. NELSON, OF KANSAS CITY, MISSOURI.

MOLD.

Application filed October 20, 1924. Serial No. 744,803.

To all whom it may concern:

Be it known that I, WILLIAM E. NELSON, a citizen of the United States, residing at Kansas City, in the county of Jackson and 5 State of Missouri, have invented certain new and useful Improvements in Molds; and I do declare the following to be a full, clear, and exact description of the invention, such as will enable others skilled in the art to 10 which it appertains to make and use the same.

My invention relates to improvements in molds designed primarily for use in the construction of concrete units, the principal object being to provide a mold of the general character disclosed in my U. S. Patent No. 1,433,905, provided with improved means for holding the removable side rails in operative position and for quickly releasing them when 20 desired.

With the foregoing in view, the invention resides in the novel subject matter herein-after described and claimed, the description being supplemented by the accompanying 25 drawings.

Figure 1 is a top plan view of a mold embodying the improved holding means for two removable side rails.

Figure 2 is an end elevation partly broken 30 away and in section.

Figure 3 is a vertical transverse sectional view on line 3—3 of Fig. 1.

Figure 4 is an enlarged vertical sectional view as indicated by line 4—4 of Fig. 1.

Figure 5 is a detail horizontal section on 35 line 5—5 of Fig. 4.

Figure 6 is a detail vertical longitudinal sectional view as indicated by line 6—6 of Fig. 1.

In the drawings above briefly described, 40 P designates a platform which includes a horizontal floor 1 and a framework 2 upon which said floor is secured, the framework being by preference mounted upon flanged 45 wheels (not shown) permitting the mold to be readily moved along trackage from one place to another.

In the construction shown, the frame 2 includes two parallel, longitudinal, angle metal bars 3 and a plurality of transverse bars 4 bolted to the upper sides of said bars 3, certain of said bars 4 being projected at one end beyond one longitudinal edge of the floor 1, as indicated at 5. The bars 3 also project beyond one end of the floor 1, and short longitudinal bars 6 are secured upon

said bars 3 and their projecting end portions, the endmost of the bars 4 and said bars 6, being jointly notched as indicated at 7 at the points at which they cross each other. 60

Two edges of the platform P are provided with stationary side rails 8 and 9 respectively, which co-act with a pair of removable side rails 10 and 11, in forming a rectangular retainer for a plurality of sectional 65 molds, such as those disclosed in the patent above referred to. These sectional molds are not shown, as the present application deals with the means for clamping the rails 10 and 11 in place and with the novel manner of mounting such clamping means. At this point, attention may be directed to the fact that the afore-mentioned rails 10 and 11 are disposed along the side and end edges 70 of the platform having the projecting ends of the bars 4 and 6. The clamping means for the rails in question are mounted on these bars, as described below.

Contacting with the lower side of each of 75 the bars 4 which is provided with a projecting end 5, and also contacting with each of the short longitudinal bars 6, at the lower side of the latter, is a horizontal plate 12, said plate having a suitable number (preferably two) of downwardly projecting ears 13 formed with a plurality of vertically spaced bolt holes 14. The inwardly turned, horizontal, inner end 15 of a vertical arm 16, is pivoted to the ears 13 by a bolt 17 which may be passed through any of the openings 80 14, so that the arm may be pivotally mounted at different elevations, bringing its upper end in proper relation with the removable rail 10 or 11, as the case may be, whether this rail possesses a comparatively short vertical width, a relatively long width, or an intermediate width, according to the thickness of the blocks to be constructed. 85

Contacting with the upper side of each of 90 the bars 4 and 6, which are equipped with the plates 12, is another horizontal plate 18, the adjacent plates 12 and 18 and the intervening bar with which they contact, being preferably secured together by thru bolts 19 and 20, and if desired, the bolts 20 may also pass through an additional longitudinal bar 21 which is shown underlying the transverse bars 4 beneath the removable rail 10. A horizontally swingable hook 22 is pivoted upon the upper side of the plate 18, which plate extends to the outer extremity of the bar by which it is carried. In pivoting the 100 105 110

hook, a bolt 23 preferably passes through it, through the plates 18 and 12, and through the bar between said plates. This hook is adapted to engage the arm 16 to hold it normally in the upright position shown in the drawings. The upper end of this arm is provided with a thrust device which is preferably in the form of a screw 24 whose outer end is provided with a hand crank 25, the inner end of said screw being engageable with the rail 10 or 11. This rail is by preference provided with an elongated cast metal plate 26 having a socket 27 to receive the inner end of the screw 24, and it is preferred that the screw shall decline toward the rail, so that when it is tightened to force this rail inwardly, it will also force it downwardly and retain it in tight contact with the floor 1 upon which it slidably rests.

Tightening of the screw 24 places a great deal of strain in an outward direction upon the hook 22 which has a tendency to shift the plate 18 outwardly. Such shifting is, of course, resisted by the three bolts 19, 20 and 23, but in order to provide additional resistance against any outward shifting of the plate 18, the inner end portion of this plate is preferably offset downwardly from its outer end portion and seated in a recess 28 formed in the upper side of the bar 4 or 6. The portion 29 of the plate, which joins the offset inner and outer end portions of said plate, bears against one end wall 30 of the recess 28 and thus an additional anchorage is provided to prevent any outward shifting of the bar 18. The construction just described, also disposes the heads of the bolts 19 and 20 in such positions as to prevent them from interfering with proper laying of the floor 1.

When placing the sectional molds (not shown) upon the floor 1, all of the arms 16 assume downwardly swung positions and the rails 10 and 11 are removed. When said molds are in place however, the rails 10 and 11 are properly positioned upon edge portions of the floor 1, the arms 16 are swung upwardly and held by the hooks 22, and the screws 24 are rotated to force the rails 10 and 11 inwardly to their proper, operative positions, the inward declinations of said screws serving also to force the rails downwardly into tight contact with the floor. After the blocks have been cast and have set, the screws 24 are loosened sufficiently to permit release of the hooks 22, and when these hooks are released, it will be seen that the arms 16 will swing downwardly out of the way, permitting easy removal of the rails 10 and 11, allowing the completed concrete units and the sectional molds to be readily taken from the platform.

Excellent results have been obtained from the construction herein disclosed and such construction is therefore preferably fol-

lowed. However, within the scope of the invention as claimed, numerous modifications may be made. It is also to be clearly understood that while the improved structure is preferably embodied in a car, adapted to be moved along a track from a casting point to a drying point, the invention could well be embodied in a stationary rather than a portable structure.

I claim:

1. A mold comprising a platform, a removable rail at one edge thereof, a vertically disposed arm spaced outwardly from said rail and edge, means pivotally connecting the lower end of said arm with the platform, a thrust device carried by the upper end of said arm for forcing the aforesaid rail inwardly, and releasable means connecting the intermediate portion of said arm with the platform to hold the arm against outward swinging under the influence of said thrust device.

2. A mold comprising a platform, a removable rail at one edge thereof, a vertically disposed arm spaced outwardly from said rail and edge, means pivotally connecting the lower end of said arm with the platform, a thrust device carried by the upper end of said arm for forcing the aforesaid rail inwardly, and a horizontally swingable hook pivoted to the platform and normally engaging said arm to hold the latter against outward swinging under the influence of the aforesaid thrust device.

3. A structure as specified in claim 1; said pivotal connecting means between the arm and platform embodying means for permitting vertical adjustment of said arm.

4. A structure as specified in claim 1; said thrust device comprising a screw threaded through the arm and declined toward said rail to force the latter downwardly against the platform while forcing it inwardly.

5. A mold comprising a platform including a floor and a frame structure for supporting said floor, said frame structure having a horizontal bar which projects beyond an edge of the floor, a removable rail at said edge of the platform, a vertical arm disposed at the outer end of said bar and having its lower end directed inwardly under said bar, means pivotally connecting said inturned end of said arm to said bar, means on said projecting end of the bar releasably engaged with the arm to hold the latter normally against outward swinging, and a rail-engaging thrust device carried by the upper end of said arm.

6. A mold comprising a platform including a floor and a frame structure for supporting said floor, said frame structure having a horizontal bar which projects beyond an edge of the floor, a removable rail at said edge of the platform, a vertical arm disposed at the outer end of said bar and hav-

- ing its lower end directed inwardly under said bar, means pivotally connecting said inturned end of said arm to said bar, a horizontally swingable hook pivoted to the upper side of the projecting end of said bar and releasably engaged with the arm to hold the latter normally against outward swinging, and a rail-engaging thrust device carried by the upper end of said arm.
7. A mold comprising a platform including a floor and a frame structure for supporting said floor, said frame structure having a horizontal bar which projects beyond an edge of the floor, a removable rail at said edge of the platform, a vertical arm disposed at the outer end of said bar and having its lower end directed inwardly under said bar, a horizontal plate contacting with the lower side of said bar and having a downward projection to which said inturned end of the arm is pivoted, a second horizontal plate contacting with the upper side of said bar and extending to the outer end of the latter, bolts passing through the two plates and the intervening bar, a horizontally swingable hook pivoted to the outer end of said second plate and releasably engaged with the arm to hold the latter normally against outward swinging, and a rail-engaging thrust device carried by the upper end of said arm.
8. A structure as specified in claim 6; the inner end of said second plate being downwardly offset from its outer end, said bar having a recess receiving said downwardly offset end, the connecting portion between the two ends of the plate being in abutting relation with one end wall of said recess for the purpose set forth.
- In testimony whereof I have hereunto affixed by signature.

WILLIAM E. NELSON.
